(57) CLAIM

The ornamental design for a combined audio player and hard disc drive, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a combined audio player and hard disc drive showing our new design;

FIG. 2 is a front elevational view thereof;

FIG. 3 is a left side elevational view thereof;

FIG. 4 is a right side elevational view thereof;

FIG. 5 is top plan view thereof; and,

FIG. 6 is a bottom plan view thereof.

Portions of FIGS. 1-6 that are shown as broken lines are for illustrative purpose only and form no part of the claimed design.
